W. Woolley

Sofa Bedstead,

Patented Oct. 3, 1831.

Oct. 3, 1831

William Woolley of New York City
Inventor

The following is copied from the above-mentioned Patent and making part of the same, containing a description in the words of the said William Woolley himself, of his improvement in the construction of said Bedstead, for Sofas or Settees.

To all whom these Presents shall come. Vide it is known that I William Woolley of the City County and State of New York have invented a new and useful improvement in the construction of said Bedstead, for Sofas or Settees, and that the following is a full and exact description of said improvement as invented by me.

The new principle as herein claimed by the subscriber, may be adapted to Sofas or Settees as followz. The bedstead may be either extended from the front, the back, or may be drawn out from the top of the sofa, in the latter case the seat and cushion form part of the Bedstead.

The ground work of the principles is the same as already secured to the subscriber in a former Patent. The Sofa or Settee, where the bedstead is extended from the front must have its seat secured by hinges at back, for rising to a vertical position. When the Bedstead is extended, the front part is also supplied with hinges, and is to be let down before the Bedstead can be drawn out.

The secret Bedstead consists of two arms, each secured by a pivot or finger joint, to opposite ends of the sofa, and within it. These arms may be made of wood or other suitable substance, and extend out at right angles from the sofa, at the required length, having moveable legs, or supports, at their extremities, which rest on the floor. The back is secured at one end to a cross-bar which fits over the projecting ends of the arms, having mortises or other contrivance for that purpose. The other side of the back is attached to a frame or leaf moving on the arm principle, as for the Counter Bedstead - (Invented by the subscriber, May 1830.) This leaf moves to stretch the back, which is also tightened by loops or cords, which pass over knobs placed on the arms for that purpose. When the Bedstead is to be extended from the back of the sofa, it consists of arms attached as before mentioned, having a cross-bar

Other arms

fixing over their ends to which one side of the drapery is attached the same as for the front. The inner side of the drapery is fastened to a horizontal shaft, hung by guy-ropes, and passing longitudinally through the body of the sofa. It is supplied with a crank for moving the bed in the body of the sofa. The drapery is bound at the ends by cords or loops which pass over knobs on the arms, for that purpose. There is also a smaller bar which fits between the arms near the sofa, having guy-ropes or loops to intersect mortises in the arms for that purpose. This bar serves as a rest or support to one side of the drapery when unrolled from the shaft. It is slipped out when the Bed is unrolled.

The sofa in this case is attached by hinges to one of the leaves, but folds at opposite angles from them. The sofa when drawn out horizontally from the sofa, extends the leaves also which are folded under it, and to one of which it is attached, thus forming one third of the width of the Bedstead.

The drapery is stretched across the leaves and tightened by a regulating pin at the back. The subscriber claims the privilege of constructing his sofa Bedsteads of wood, or any suitable material.

The superiority of these Bedsteads over all others, is that the beds & bedding are enclosed in a tight box which effectively excludes all dust and air necessary to the existence of insects.
